FREQUENCY DIVIDER

Stuart William Seeley, Roslyn Heights, N. Y., assignor to Radio Corporation of America, a corporation of Delaware

Application February 14, 1947, Serial No. 728,394

11 Claims. (Cl. 250—36)

1

This invention relates to frequency dividers, and more particularly to a simplified and improved frequency divider.

An object of the invention is to provide a stable frequency divider employing a single tube and a delay line in circuit therewith, and capable of dividing by two, four, six, etc., depending upon the constants of the delay line.

Another object of the invention is to provide a frequency divider which can be keyed to start or stop within a fractional period of a cycle of the frequency to be divided, and which provides uniform output impulses during the entire keying "ON" interval without variation of either amplitude or phase of these impulses during the "ON" interval.

Another object of the invention is to provide a stable frequency divider which may be keyed without the introduction of transients.

Another object of the present invention is to provide a frequency divider which can be keyed and satisfies the requirements (1) of a negligible leakage of the input energy to the output terminals, (2) provides output impulses whose wave forms are substantial replicas of those portions of the input wave forms which have a given polarity, and (3) provides (during a keying interval) a predetermined number of uniformly spaced impulses whose wave forms and peak amplitudes are identical.

Although many types of frequency dividers are known in the art, such dividers suffer from numerous disadvantages; and none of them, having the simplicity of the frequency divider of the present invention, fulfill all of the objects stated above.

A more detailed description of the present invention follows in conjunction with the drawings, wherein:

Fig. 1 illustrates a simplified form of frequency divider embodying the principles of the present invention;

Figs. 2a, 2b and 2c are graphs given in explanation of the operation of the frequency divider of the invention; and

Fig. 3 illustrates a preferred form of frequency divider of this invention.

The same or equivalent parts of the embodiments of Figs. 1 and 3 are labeled by the same reference characters.

Referring to Fig. 1, there is shown a frequency divider comprising a triode vacuum tube 10 whose anode is connected through the secondary winding of a transformer TR to one end of an artificial line TL. The other end of the line TL is

connected through a lead 12 to the grid of the tube. Line TL is a constant K filter which is composed of a multiplicity of series inductances and shunt capacitances. That end of line TL which is connected to the grid is terminated by a resistor 13 whose value is equal to the surge impedance of the filter. One side of the line TL is connected to ground. The cathode of the tube 10 is also grounded. The primary winding 10 of the transformer TR is connected to the source of energy whose frequency is to be divided. The output terminals, from which spaced impulses are obtained, are designated 14.

The operation of Fig. 1 may be better understood by reference to the graphs of Figs. 2a, 2b and 2c. Let it be assumed, for example, that the energy of the driving source is a sine wave of 360 kilocycles. Fig. 2a graphically shows such a sine wave, whose value is zero at times A', A, B, C, D, E, F etc. The positive half cycles of the sine wave of Fig. 2a cause current to flow through the tube 10 in the absence of a negative grid voltage. However, when the tube conducts on a first positive half cycle, a voltage drop (equal to the surge impedance of the filter TL multiplied by the anode current flowing through the tube) is impressed on the input of the filter TL. This voltage drop constitutes an impulse which is shown in Fig. 2b between times A and B, and this impulse travels down the line TL toward the resistor 13, arriving at the terminating resistor 13 between the times C and D as shown in Fig. 2c. This impulse in Fig. 2c is of negative polarity with respect to ground and is impressed upon the grid of the tube 10 by way of conductor 12. The time constants of the line TL are so chosen that the negative impulse impressed on the grid occurs during the time when the immediately succeeding positive half cycle of Fig. 2 is impressed on the anode of the tube. This negative impulse which is applied to the grid of tube 10 is of such magnitude as to prevent the tube 10 from drawing current during its occurrence. It will thus be seen from an inspection of the graphical representation of Figs. 2a, 2b and 2c that the tube 10 draws current only during alternate positive half cycles of the applied input wave.

Although the system of Fig. 1 has been described with particular reference to a frequency halver, it will be obvious that the constants of the filter TL may be selected so as to delay the negative pulses applied to the grid by periods of two, three or any integral number of complete cycles of the input wave. For instance, if the delay time

of the filter TL is equal to two cycles of the input wave, both the first and second positive portions of that wave will cause current to flow in the vacuum tube 20, and a pair of negative pulses corresponding to those anode current pulses will be applied to the input of the filter TL. This pair of pulses being subjected to the two cycle delay time of the new filter TL, will now be impressed on the grid during the third and fourth positive half cycles of the input wave and prevent the passage of anode current at those particular times. Thus, anode current will flow for two half cycles, be cut off for two half cycles, again flow for two half cycles, etc. In this manner the output energy will have a component whose frequency is one-quarter of that of the input wave. In the same manner, if the filter were designed to have a delay time equal to three cycles of the input wave, the output of the device would consist of groups of three pulses followed by a quiescent period equal to three cycles, etc., thus giving an output component at one-sixth of the frequency of the input wave.

Fig. 1 has been illustrated and described in order to explain the broad principles of the invention. However, for certain applications, the system of Fig. 1 may require additional features to overcome leakage of the input energy to the output terminals.

The system of Fig. 3 is a preferred embodiment of the invention and is designed to minimize leakage of the input wave to the output terminals 14. Referring to Fig. 3 in more detail, there is shown a pentode vacuum tube 20 whose anode is connected via lead 21 to terminal T1 of the secondary 22 of the transformer TR'. Terminal T2 of transformer TR' is connected via lead 23 to the input end of an artificial line or constant K filter TL. The output end of the line TL is terminated by a resistor 13 whose value is equal to the surge impedance of the line TL, and is also connected via lead 12 to the first grid of the vacuum tube 20. The input wave whose frequency is to be divided is applied to the primary winding of the transformer TR'.

If the screen grid SG of vacuum tube 20 is supplied with positive voltage and the suppressor grid SP is connected to the cathode (as shown), the portion of the circuit of Fig. 3 so far described would operate exactly as explained in connection with Fig. 1. However, if the device is to divide frequencies of the order of a few hundred kilocycles or higher, the normal capacitive leakage between the terminal T1 of the secondary 22 and ground may cause current at the applied frequency to flow through the filter TL regardless of whether or not tube 20 is conducting, and thus impress an undesirable amount of the applied frequency between the output terminals 14. To overcome this difficulty, secondary 22 of transformer TR' has been extended to a third terminal T3 in order to produce a potential opposite to that applied to the anode, and a balancing condenser 25 is connected between terminal T3 and ground in order to allow for neutralization of the capacity currents in accordance with well-known principles. In case there should also be conductive leakages of the input energy to ground, these may also be neutralized by the inclusion of a resistor of the proper size from either terminal T1 to ground, or from T3 to ground, as the case may require. Resistor R is one such resistor and can be eliminated in many cases. If desired, the entire secondary of transformer TR' may be resonated to the input frequency by means of a con-

denser 26 shunted between terminals T1 and T3. This procedure, however, is only applicable in the case wherein the input frequency is a sine wave.

The system of Fig. 3 lends itself to keying, and this may be accomplished by applying a square wave keying pulse of positive polarity to the screen grid SG. The occurrence time and repetition rate of this square wave keying pulse should be synchronously related to the frequency of the drive source, so that the starting edge of the keying pulse occurs during the time interval when the anode of the tube 20 is negative with respect to the cathode. In this way, the frequency divider of the invention will be ready to operate on the succeeding positive half cycle of the input wave. The keying wave may, if desired, have a duration equal to ten or more complete cycles of the input wave energy, and all of the output pulses during that interval will occur at a sub-multiple rate with respect to the input frequency and will be uniformly spaced and have the same peak amplitude and the same wave form.

It should be noted that the anodes of the tubes of Figs. 1 and 3 have not been provided with a positive polarizing B+ potential such as is customarily provided in conventional circuits. This anode polarizing potential is not necessary in this case because the driver voltage has sufficient magnitude to cause anode current to flow during the desired intervals. It should be distinctly understood, however, that the invention is not limited to this specific arrangement since, if desired, an anode polarizing potential may be supplied. Although the terminating resistor 13 has been shown connected to the output end of the artificial line it should be understood that, if desired, this resistor may be connected to the input end of the line, or the line may be terminated on both ends by resistors. Another alternative still within the scope of this invention is to construct the artificial line of elements with sufficient dissipation so that no termination is necessary.

The invention is not limited to the specific embodiments described and illustrated. For instance, other means for keying the device of the invention may employ the cathode impedance of a vacuum tube shunted across the input to the transmission line TL to prevent the initiation of voltage pulses in that line in the absence of a keying wave of negative polarity applied to a control element of the vacuum tube used to supply this cathode shunting impedance.

What is claimed is:

1. A frequency divider comprising a vacuum tube having an anode, and a grid, a delay line having one terminal connected to said anode and another terminal connected to said grid, a source of energy whose frequency is to be divided coupled to the anode of said tube in such manner as to supply sufficient polarizing potential to cause said tube to draw current during predetermined portions of the input wave, to thereby cause a voltage wave to travel along said line from the terminal connected to said anode, said delay line having such constants between said terminals and being so constructed and arranged that the voltage wave traveling thereover when said tube draws current is delayed a predetermined integral number of cycles of the input wave before being applied to said grid in such sense and magnitude as to prevent said tube from drawing current during the interval the delayed voltage wave is applied to said grid, said frequency

divider being free from inductively coupled feedback circuits between anode and grid and also free from operation on the relaxation oscillator principle.

2. A frequency divider comprising a vacuum tube having an anode, a cathode and a grid, a constant K filter line having one end connected to said anode and its other end connected to said grid, a connection from said cathode to one side of said line, a terminating resistor connected to said line, means including a driver source for supplying the frequency to be divided to the anode of said tube through a transformer, said frequency divider being so constructed and arranged that there is an absence of anode current flow therein in the absence of applied waves from said driver, said applied waves having such magnitude as to cause said tube to draw current at certain predetermined intervals, to thereby produce a voltage pulse whenever said tube draws current and which travels along said line from the anode end to the grid end, said filter line having such constants that it produces a delay in the voltage pulse traveling along its length which is equal to a predetermined integral number of cycles of the applied wave.

3. A frequency divider comprising a pentode vacuum tube having an anode, a cathode, and a plurality of grids, an artificial line having one end connected to said anode and its other end connected to a grid, a connection from said cathode to said artificial line, means for supplying fundamental frequency waves to said anode through a transformer, said frequency divider being so constructed and arranged that said tube does not draw current in the absence of applied waves from said means, said tube producing a voltage pulse whenever it draws anode current and which pulse travels along said line, said line having such constants that it produces a delay in the voltage pulse traveling along its length which delay is equal to a predetermined integral number of cycles of the fundamental frequency wave, and a source of keying waves coupled to another grid of said tube, the repetition rate of said keying waves being synchronously related to the waves of said fundamental frequency and so phased that the starting edge of the keying wave occurs during the time interval that said tube is not drawing current.

4. A frequency divider comprising a vacuum tube having an anode, a cathode, and a grid, a delay line having one terminal connected to said anode and another terminal connected to said grid, a source of sinusoidal wave energy whose frequency is to be divided coupled to said anode of said tube in such manner as to cause said tube to draw current during predetermined portions of the input wave to thereby cause a voltage wave to travel along said line from the terminal connected to said anode, said delay line having such constants between said terminals that the voltage wave traveling thereover when said tube draws current is delayed a predetermined integral number of cycles of the input wave before being applied to said grid, and means for keying said tube by supplying to said frequency divider a keying wave of predetermined polarity at intervals which are synchronously related to the frequency of the input wave and so phased that the positive rising edge of the keying wave occurs

6
during the time interval that said anode is negative with respect to the cathode.

5. A frequency divider comprising a vacuum tube having an anode, a cathode and a grid, a delay line having one end connected through a coil to said anode and its other end connected to said grid, a connection from said cathode to one side of said line, means for supplying to said coil the frequency to be divided to enable said tube to draw current during predetermined portions of the input wave, to thereby cause a voltage wave to travel along said line from the terminal connected to said anode, said delay line having such constants between said terminals that the voltage wave traveling thereover when said tube draws current is delayed a predetermined integral number of cycles of the input wave before being applied to said grid in such sense and magnitude as to prevent said tube from drawing current during the interval the delayed voltage wave is applied to said grid.

6. A frequency divider comprising a vacuum tube having an anode, a cathode and a grid, a delay line having one end connected through a coil to said anode and its other end connected to said grid, a connection from said cathode to one side of said line, a connection from said cathode to ground, means for supplying to said coil the frequency to be divided, an inductive extension for said coil, and a balancing condenser connected between ground and that terminal of said extension which is furthest removed from said coil, means for preventing said tube from drawing current in the absence of energy from said source, said tube producing a voltage wave whenever it draws current which travels along said line in a direction away from the anode terminal of said line, said delay line having such constants between said terminals that the voltage wave traveling thereover when said tube draws current is delayed a predetermined integral number of cycles of the input wave before being applied to said grid in such sense and magnitude as to prevent said tube from drawing current during the interval the delayed voltage wave is applied to said grid.

7. A frequency divider comprising a vacuum tube having an anode, a cathode and a grid, a delay line having one end connected through a coil to said anode and its other end connected to said grid, a connection from said cathode to one side of said line, a connection from said cathode to ground, a means for supplying to said coil the frequency to be divided, an inductive extension for said coil, and a balancing condenser connected between ground and that terminal of said extension which is furthest removed from said coil, a condenser across said coil and extension for tuning the same to the frequency of said source, means for preventing said tube from drawing current in the absence of energy from said source, said tube producing a voltage wave whenever it draws current which travels along said line in a direction away from the anode terminal of said line, said delay line having such constants between said terminals that the voltage wave traveling thereover when said tube draws current is delayed a predetermined integral number of cycles of the input wave before being applied to said grid in such sense and magnitude as to prevent said tube from drawing current during the interval the delayed voltage wave is applied to said grid.

8. A frequency divider comprising a vacuum tube having an anode, a cathode and a grid, a

delay line having one end connected through a coil to said anode and its other end connected to said grid, a connection from said cathode to one side of said line, a connection from said cathode to ground, a terminating dissipative resistor coupled to said delay line, a source of energy whose frequency is to be divided coupled to said coil, an inductive extension for said coil, and a balancing condenser connected between ground and that terminal of said extension which is furthest removed from said coil, a condenser across said coil and extension for tuning the same to the frequency of said source, means for preventing said tube from drawing current in the absence of energy from said source, said tube producing a voltage wave whenever it draws current which travels along said line in a direction away from the anode line terminal, said delay line having such constants between said terminals that the voltage wave traveling thereover, when said tube draws current is delayed a predetermined integral number of cycles of the input wave before being applied to said grid in such sense and magnitude as to prevent said tube from drawing current during the interval the delayed voltage wave is applied to said grid, said means including a source of keying pulses whose repetition rate is lower than and synchronously related to the frequency of said source of energy.

9. In a vacuum tube frequency divider containing a control electrode, the method of dividing the frequency of an input wave which comprises causing said tube to conduct current at certain predetermined intervals of the input wave, producing a voltage pulse whenever said tube draws current, delaying this voltage pulse a predetermined integral number of cycles of the input wave, applying said delayed voltage pulse to a control electrode of the vacuum tube in such sense and magnitude as to prevent said tube from drawing current during the time said delayed voltage pulse is applied to said control electrode, and applying keying waves to said vacuum tube at times synchronously related to the frequency of said input waves but such that the start of the keying wave occurs during the time interval that said tube does not draw current.

10. A frequency divider comprising a vacuum tube having an anode, a cathode and a grid, a filter line having one end connected to said anode and its other end connected to said grid, a connection from said cathode to one side of said line, a terminating resistor connected to said line, means positively coupled to said anode for supplying the frequency to be divided thereto, said

frequency divider being so constructed and arranged that there is an absence of anode current flow therein in the absence of applied waves from said means, said applied waves having such magnitude as to cause said tube to draw current at certain predetermined intervals, to thereby produce a voltage pulse whenever said tube draws current and which travels along said line from the anode end to the grid end, said filter line having such constants that it produces a delay in the voltage pulse traveling along its length which is equal to a predetermined integral number of cycles of the applied wave.

11. A frequency divider comprising a vacuum tube having an anode, a cathode and a pair of control electrodes, a section of transmission line connected at one end to said anode and at its other end to one of said control electrodes, means coupled to said anode for supplying thereto waves of the frequency to be divided, said waves having positive and negative peaks, said frequency divider being so constructed and arranged that there is an absence of current flow therein in the absence of said waves being supplied to said anode, said applied waves having such magnitude as to cause said tube to draw current at predetermined intervals to thereby produce a voltage pulse whenever said tube draws current and which travels along said line from the anode end to the grid end, said line having such constants that it produces a delay in the voltage pulse traveling along its length which is equal to an integral number, including unity, of cycles of the applied wave, and means for supplying keying pulses to the other grid of said tube, the repetition rate of said keying pulses being synchronously related to the waves whose frequency is to be divided and so phased that the starting edge of the keying wave occurs during the time interval that said anode is negative relative to the cathode.
